UNITED STATES PATENT OFFICE.

ORANGE O. OZIAS, OF DAYTON, OHIO.

DESIGN FOR A SCALE BASE-PLATE.

SPECIFICATION forming part of Design No. 28,947, dated June 28, 1898.

Application filed June 6, 1898. Serial No. 682,789. Term of patent 14 years.

To all whom it may concern:

Be it known that I, ORANGE O. OZIAS, of Dayton, county of Montgomery, and State of Ohio, have invented a certain new and useful Design for a Scale Base-Plate, of which the following is a description, reference being had to the accompanying drawings, forming a part hereof, and in which like figures refer to like parts.

In the drawings, Figure 1 is a plan view of a scale base-plate formed in accordance with my design, and Fig. 2 is a sectional elevation hereof on line $x x$ of Fig. 1, these two figures being deemed necessary to fully illustrate my design.

The leading or material feature of my design consists of a circular plate having a circular ring and a series of serrations arranged in a circle, formed on one side of said plate, said ring and said circle of serrations being concentric.

In the drawings, 10 represents the circular plate, 11 the circular ring, formed on one side of and projecting from said plate, and 12 illustrates the serrations formed upon the outer 25 edge of said plate 10, said ring 11 and circular row of serrations 12 being concentric with said plate 10. Said row of serrations is formed of a series of depressions 13 in the edge of one face of said plate 10 and connecting with a 30 corresponding series of depressions 14, formed in the periphery of said plate 10.

What I claim is—

The design for a scale base-plate substantially as herein shown and described. 35

In witness whereof I have hereunto set my hand this 27th day of May, 1898.

ORANGE O. OZIAS.
